UNITED STATES PATENT OFFICE.

REGINALD A. FESSENDEN, OF BROOKLINE, MASSACHUSETTS, ASSIGNOR TO SUBMARINE SIGNAL COMPANY, OF PORTLAND, MAINE, A CORPORATION OF MAINE.

ELIMINATING DISTURBING ENERGY.

Application filed August 20, 1917. Serial No. 187,121.

To all whom it may concern:

Be it known that I, REGINALD A. FESSENDEN, of Brookline, in the county of Norfolk and State of Massachusetts, a citizen of the 5 United States, have invented a new and useful Improvement in Eliminating Disturbing Energy, of which the following is the specification.

My invention relates to the generation, 10 transmission, and utilization of energy and more particularly to the generation and receipt of signals and still more particularly to the elimination of disturbing signals and influences and water noises, such as cause 15 disturbance in submarine signalling and detecting submarines.

The object of my invention is to obtain increased efficiency in these lines.

The drawing shows diagrammatical mechanism embodying my invention.

In Fig. 1, 11 is a receiver for signals; for example, as shown, an oscillator, such as described in U. S. Patent No. 1,167,366 which translates such signals into electrical 25 impulses and hence may be termed a receiving transmitter. The leads 12 and 13 of the oscillator go to a rectifier 14, the frequency of which is adjusted by the regulator 15 for example of the type described 30 by applicant in his paper on "Wireless telephony" (Transactions of the American Institute of Electrical Engineers, July, 1908), or as shown a simple rheostat. The leads from the rectifier are connected 35 through the choke coils 16, 16' to an interrupter, 18, the frequency of which is regulated by the regulator 23. 15 and 23 may be field rheostats which are used as required.

The circuits containing the choke coils 16, 40 16' may be shunted by the condensers 17, 17', as shown as is well known in the art of producing practically steady rectified currents from alternating currents (see Steinmetz, Transient Electrical Phenomena, 45 pages 236-248).

The leads from the interrupter 18 may proceed through the amplifier 19 and leads 21, 20 to the ear piece 22.

In operation the interrupter 18 is adjusted 50 to any suitable frequency, as found by experiment. The rectifier 14 is then varied until the operator listening in with the ear piece 22 hears the signal or noise which he desired to hear come in as plainly 55 as possible.

The action of the apparatus appears to be that if the submarine emits a note of frequency 30, this is received by the oscillator 11 together with water noises and other disturbing sounds. If no commutator 60 were used but merely the receiver 22, the water noises and disturbing noises made by auxiliaries, etc., would drown out the noise of the submarine and amplification would make matters worse as the ordinary amplifiers usually amplify disturbing noises more than submarine noises.

With the arrangement shown, however, if the rectifier 14 be adjusted to a frequency 30, then the sound emitted by the submarine 70 having frequency 30 will be rectified to substantially continuous current and later passed through the choke coils 16, 16', which may have an inductance of the order of a henry the condensers 17, 17' having any 75 suitable value, as is well known in the art (see Steinmetz, Transient Electrical Phenomena, pages 236-248), without substantial loss or diminution, and these continuous or slowly pulsating currents being received by the interruptor 18 will be broken up into a high frequency current of that pitch to which the ear is most sensitive, approximately 920, and the effects they produce may be heard either directly on the 80 receiver 22 or, being free from disturbing effects produced by water noises, can be amplified before reaching the receiver 22.

In this way the water noises and other disturbing noises are eliminated because 90 having as a rule frequencies different from 30 they will not be rectified by the rectifier 14 into continuous or slowly pulsating currents but will remain alternating currents and will even, in most cases, have their frequency raised by the commutator so that the choke coils 16, 16' and condenser 17 will entirely prevent any except the most minute portion of them from passing onward to 18, and the minute remainder will be still further diminished by 18.

This combination acts as a very simple, efficient, and very sharply selective variable filter and is hence of use wherever such filters are desired, and is also of use for 10 other purposes. This method of selecting or filtering out disturbing impulses has many advantages over the older resonance methods discovered by Hertz, Tesla, applicant and others. It will do many things 11

which the resonant method cannot accomplish. For example:-

1. If the frequency of the signal is so low as to be inaudible, say 10 per second, then after selection by resonance methods it will be inaudible, and must be "chopped" in accordance with the method invented by applicant, and for which a patent was allowed him. But this "chopping" will take place at varying points on the wave, and by Fourier analysis this can be shown equivalent to a broad band of frequencies, thus weakening the selectivity and preventing further selection. With the present method this is not the case; the final note is pure and even.

2. If the frequency is so high as to be inaudible, with the old resonance method it must be chopped, with great loss of efficiency. Or if passed through a liquid barretter or tellurium receiver or the like, there will be great loss due to the resistance of the receiver, amounting generally to thousands of ohms, which loss is avoided in the present method.

3. Harmonics can pass in resonance methods, which cannot pass with present method.

4. With this method, the same device has been operated over a range of more than 1 to 1,000, i. e. the maximum frequency being more than 1,000 times the minimum. With resonance methods, the inductance would have to be 9,000,000 times as great for the minimum frequency as for the maximum.

5. The selectivity is substantially independent of the length of the wave train, i. e. is substantially as sharp for a train of 4 wave lengths as for one of 40; which is not the case with resonance methods.

It will be seen that the method herein described is a radically new means of producing selectivity. Heretofore this has been accomplished by resonance methods, but the method herein described is entirely independent of resonance as it will be noted that if a desired frequency is to be selected the first commutating rectifier 14 is adjusted to operate at the desired frequency and thereby turns the desired impulses into a substantially continuous current, while all the undesired frequencies remain of an alternating current character. That this substantially continuous current produced from the oscillators of the desired frequency flows without substantial loss or impedance through the choke coil 16 and after flowing through it is acted upon by the second commutator to produce a note or indication at any desired frequency, whereas all the undesired frequencies were kept back by the choke coil 16. In practice selective curves obtained with the apparatus hereby described have been found to be much sharper than those obtained by resonance methods.

What I claim is:

1. Apparatus for the utilization of the energy of electric impulses; comprising a generator of electric impulses, receiving conductors, an interrupter, a choke coil, a second commutator, and a device for utilizing the energy of electric currents, in series in the order given; whereby electric currents flowing from the receiving conductors to the first commutator, and of a desired frequency, are commutated into substantially continuous currents by means of the first commutator; and currents of undesired frequencies are not so commutated; and the passage of the energy of the currents of undesired frequencies is opposed by the choke coil, while the passage of the substantially continuous current is not so opposed by said choke coil; and said substantially continuous current is then commutated to periodic currents of a desired frequency by the said second commutator; and said periodic currents utilized in said electric energy utilizing device.

2. The method of selecting periodic electric current of a desired frequency, flowing in an electric circuit, from currents of undesired frequencies flowing in said electric circuit; which consists in first commutating said current of desired frequency into substantially continuous current; secondly opposing the flow of said currents of undesired frequencies while permitting the flow of said substantially continuous current; and thirdly commutating said substantially continuous current into current of a desired periodicity.

3. The method of selecting from other and undesired impulses, impulses of a desired frequency, and of utilizing said impulses of a desired frequency, which consists in rectifying said impulses of a desired frequency by a commutating rectifier operating at a commutation frequency substantially the same as the frequency of the impulses to be utilized, then passing said rectified impulses through an electric circuit element which is resistant to the flow of non-rectified impulses, and substantially non-resistant to the flow of rectified impulses, thereby permitting mainly and substantially only the rectified impulses to pass, and then interrupting, by a second interrupting device, said rectified impulses into interrupted impulses of the frequency at which it is desired to utilize said impulses.

4. That method of eliminating disturbing noises from sounds desired to be received which consists in receiving said noise and sound impulses upon a receiver whereby they will be transformed into electrical impulses, adjusting a rectifier to the frequencies of the sound impulses desired to be received and transmitting said electrical impulses thereto whereby those impulses of the

frequency of the rectifier will pass there-
through and be rectified into a continuous
current, separating said rectified current
from all unrectified impulses, breaking up
5 said rectified current into a high frequency
current and delivering it to an indicator.

5. Apparatus for the utilization of the
energy of electric impulses, comprising re-
ceiving conductors, a commutator, a choke
10 coil, a second interrupter, and a device for
utilizing the energy of electric currents, in
series in the order given; whereby electric
currents flowing from the receiving con-
ductors to the first commutator, and of a de-

sired frequency, are commutated into sub- 15
stantially continuous currents; by means of
the first commutator; and currents of unde-
sired frequencies are not so commutated;
and the passage of the energy of the cur-
rents of undesired frequencies is opposed by 20
the choke coil, while the passage of the sub-
stantially continuous current is not so op-
posed by said choke coil; and said substan-
tially continuous current is then commu-
tated to periodic currents by the second 25
commutator; and said periodic currents
utilized in said energy utilizing device.

REGINALD A. FESSENDEN
